UNITED STATES PATENT OFFICE

112,870

DESIGN FOR A GLIDER FRAME

Louis Vavrik, Rossford, and Charles E. Friesner,
Toledo, Ohio, assignors to The Hettrick Manufacturing Company, Toledo, Ohio, a corporation of Ohio

Application July 27, 1938, Serial No. 78,772

Term of patent 3½ years

To all whom it may concern:

Be it known that we, Louis Vavrik and Charles E. Friesner, residents of Rossford, Wood County, Ohio, and Toledo, Lucas County, Ohio, respectively, have invented a new, original, and ornamental Design for a Glider Frame, of which the following is a specification, reference being had to the accompanying drawing, forming a part thereof.

In the drawing:

Figure 1 is a perspective view of the glider frame, showing our new design; and

Figure 2 is an end elevational view thereof.

We claim:

The ornamental design for a glider frame, as shown.

LOUIS VAVRIK.
CHARLES E. FRIESNER.
